[57] **CLAIM**

The ornamental design for an aspirator for emergency cardio-pulmonary resuscitation, as shown and described.

DESCRIPTION

FIG. 1 is a front perspective view of an aspirator for emergency cardio-pulmonary resuscitation, showing my new design;

FIG. 2 is a front elevational view thereof;

FIG. 3 is a side elevational view thereof, the opposite side being identical;

FIG. 4 is a bottom plan view thereof; and

FIG. 5 is a cross-sectional view taken along line I—I of FIG. 2.

Both sides are the same.

FIG. 1

FIG. 2

FIG. 3

FIG. 4

FIG. 5
